Application September 3, 1947, Serial No. 771,896

3 Claims. (Cl. 219—26)

1

This invention relates to an electrical tool which may be used to generate heat to raise the temperature of any electrically-conducting material, as necessary for soldering, welding, brazing, drawing or annealing of such material. It has for an object to provide an improved tool of this character which may have a pair of electrodes to engage and clamp the work, and in which either one or both are movable toward each other to firmly clamp the work between the current-carrying electrodes during the entire operation, regardless of whether the current is actually flowing through the electrodes.

Another object is to provide a construction including means for protecting the current-carrying electrodes against over-stressing of the electrode material regardless of the pressure applied to the electrode operating means.

Another object is to provide a construction in which the electrodes are automatically returned to and retained in the open or separated position when the tool is not in use.

A further object is to provide a self-contained switch means in this type of device which is controlled by an actuating lever which changes the relative positions of the electrodes and applies the electrode clamping pressure.

A further object is to provide the combination of a clamping means for holding the work firmly between the electrodes, with a quick-acting self-contained switch means to control the current for raising the temperature of a piece of electrically conducting material, and which may be used for maintaining that temperature within reasonably accurate limits for a prolonged period, or which may be used for gradually raising or lowering the temperature of such a piece of material, as may be required for certain drawing or annealing operations or for brazing, soldering or welding together two or more pieces of such material.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a top plan view of one form of the device which may be used as a hand tool, and is readily portable for use as a plier type of device;

Fig. 2 is a side view with one side member of the supporting structure or housing removed, showing the electrodes and the other cooperating

2

elements in side elevation, the various elements being shown somewhat diagrammatically and without going into details, to simplify the drawings, and

5 Fig. 3 is a transverse section substantially on line 3—3 of Fig. 2.

The device shown comprises a pair of electrodes 5 and 6 preferably of carbon or some similar conducting material, or they could be of metal if preferred. These electrodes are electrically insulated from each other except when moved into actual contact with each other or when they are in common contact with some electrically conducting material. They are also electrically insulated from the supporting structure of the tool and other operating elements, except where necessary for maintaining the electrical current. One of these electrodes may be fixed and the other movable, or they may be both movable as 10 found desirable, but to simplify the construction and for ordinary purposes it is preferred to have one of them fixed or stationary, in this case the electrode 5, and the other electrode 6 movable toward and from the fixed electrode 5. In the 15 present structure the electrode 6 is mounted on a conducting lever 7 pivoted to the housing or supporting structure 8 by any suitable means at 9, so that by operation of this lever electrode 6 may be shifted toward and from the fixed electrode 5 to grip and hold a work piece between them, as will later be described. The fixed electrode 5 may be mounted on a support 10 secured in a recess or slot 11 formed in the housing or supporting structure 8, by any suitable 20 means such as the screw 12, which may also be used as a binding screw for connecting an electrical conductor to the support 10, the support 10 being of electrical conducting material. It is also preferred that the electrodes themselves be 25 detachably supported on their respective supports so that they may be readily removed for renewal or repair. In the present case they are shown as mounted by suitable screws 13 with a tongue 14 on each electrode seated in a fork 15 30 in their supports, but any other suitable mounting and securing means may be employed.

The form of the electrodes may vary with different applications of the tool as is found desirable, but in general it has been found most convenient and desirable to have the electrodes approximately square or rectangular in cross section with the abutting or opposed clamping surfaces substantially flat and approximately parallel with respect to each other when the electrodes 35 are in the closed position, and with the ends

tapered to a more or less blunt point. However, it should be understood that the exact form or shape of these electrodes may be varied as required for different uses of this tool. It will be seen from the drawing that the movement of the electrodes with respect to each other in the form shown is generally similar to the relative movement of the jaws of a pair of tongs or pliers.

It has been found more convenient to manufacture the lever 7 of metal and use it as a conductor for carrying current to the electrode 6, but it will be understood the device is not limited to this structure, as the lever may be made of some suitable nonconducting material, in which case it would carry a conductor connected with the electrode. In the drawing a conductor 16 is connected to the lever 7 and a suitable conductor 17 is connected to the support 10 carrying current to the respective electrodes 5 and 6. The conductor 17 may be led to a suitable source of current supply (not shown) but the other conductor 16 is connected to one contact 19 of a suitable switch enclosed in the housing or supporting structure 8. The other switch contact is shown at 20 mounted on any suitable means, such as a flexible spring support 21 to which the other conductor 22 from any suitable source of current supply is connected, and which is constructed to tend to keep the switch contacts separated.

The movable contact is operated by an actuating lever 23 pivoted in the supporting structure or housing 8 by any suitable means, such, for example, as the connecting transverse bolt 24. This lever is preferably of non-electrically conducting material, such, for example, as some molded plastic, and such construction eliminates the necessity of providing electrical insulation between this lever and the switch contact 20 and the electrode carrying lever 7, but it will of course be understood the lever 23 may be made of other suitable materials, and if it is of an electrically conducting material suitable insulation must be provided when required. Movements of the lever 23 are limited by a suitable stop means such, for example, as a pin 25 mounted in the housing 8 and passing through a curved slot or other suitable opening 26 in the lever; this stop pin cooperating with the ends of the slot or sides of the opening to limit movements of the lever in opposite directions.

A return spring 27 is interposed between the electrode carrying lever 7 and the supporting structure or housing 8, and there is an actuating spring 28 between the hand lever 23 and the lever 7. The spring 27 is designed to be of less strength or have less thrust than that of the actuating spring 28, so that the spring 27 will yield under operating thrust from the spring 28. The spring 27 is to return the lever 7 and the operating lever 23 to their normal or inoperative position shown, when manual pressure on the lever 23 is released. This action of the spring 27 serves a double purpose, the first being to maintain the movable electrode 6 in the open position ready for the next operation when the tool is not being used. The second purpose of this spring is to disengage the actuating lever 23 from the switch 20 when the pressure on this lever is released, so that the switch is always in the open position when the tool is not in use; thus insuring that unless the tool is actually in use the circuit to the electrodes is open.

The manually operable lever 23 is mounted so as to project through a suitable slot or opening 29 in the top of the supporting structure or hous-

ing 8 and is so shaped that its upper edge portion projects above the top surface of the housing 8 where it is readily available for pressure of the hand of the operator while gripping this housing.

This housing or supporting structure provides a rigid mounting for all the parts of the device and maintains each part in its proper relation to the other parts. In the form shown it is made of non-electrically-conducting molded plastic material of generally oval shape to fit the hand, and is in two sections 30 and 31 to facilitate manufacture and also mounting of the various elements of the device, each section being provided with a cavity so that when the parts are connected they form a compartment 32 in which the various elements are mounted and where they are enclosed so as to be thoroughly protected. The making of these sections of plastic insulating material simplifies the problem of electrical insulation, as various electrical parts may be mounted directly on this structure, but it will be understood the housing may be made of other materials if found desirable, and if it is made of metal or other electrically-conducting material, then suitable insulation must be provided for the various electrical conducting elements or current-carrying parts. The sections 30 and 31 may be secured together by any suitable means, such, for example, as the screw 24 and the bolts 33. As the screw 23 is also used as a pivot support for the actuating lever 23, it is preferably made in two sections, with a screw section 34 threaded into the tapped end of the body section 35, or other suitable type of securing means may be used as found desirable.

The operation is as follows:

In the drawing, the tool is shown in released position with the parts ready for operation. If it is assumed, for example, that two pieces of copper wire are to be soldered together, they will be placed in contact with each other in the space between the electrodes 5 and 6. The operator then applies manual pressure to the actuating lever 23. This pressure is transmitted through the actuating spring 28 to the electrode carrying lever 7 which swings about its pivot 9, compressing the spring 27 as this is a lighter spring of less thrust than the spring 28, and shifts the electrode 6 toward the electrode 5 and the two pieces of wire. As the pressure on the lever 23 is further increased the electrode 6 firmly clamps and holds these wires between the two electrodes and maintains these wires in contact with each other and in contact with both electrodes. The parts are so designed and arranged that although the electrodes 5 and 6 are now in electrical contact through the copper wires, the switch contacts 19, 20 are still in the open or separated position and no current will flow through these electrodes at this time, these first movements being to properly grip the elements to be operated upon, and also to establish proper contact between them and the electrodes 5 and 6 before any current flows. If now the operator still further increases the pressure on the actuating lever 23 this lever will be further depressed, but as the two wires, or the work to be operated upon, are now firmly clamped between the electrodes 5 and 6 further movement of the secondary or electrode lever 7 is thereby prevented. Therefore, on further movement of the actuating lever 23 the actuating spring 28 is compressed, permitting further movement of the lever 23, and spring 28 is so designed that when it is in compression it exerts sufficient pressure against the lever 7 to firmly hold the work, in this case the two copper wires, between electrodes

5 and 6, but the thrust of the spring 28 is not great enough at any point in the movement of the lever 23 to cause overstressing of the electrode material. This is a very important feature of this invention, as it permits necessary movement of the actuating lever 23, but at the same time controls or limits the clamping force or pressure of the electrodes, preventing any possibility of breaking or injuring these electrodes or the work held by them, and particularly as it permits the use of carbon for these electrodes, which is one of the materials most suitable for such elements, but is of relatively low tensile strength and therefore liable to fracture if overstressed. It also prevents the placing of too great pressure on the articles being operated upon, and provides substantially uniform pressure of the electrodes throughout the entire heating operation which will now take place after the work pieces are properly positioned and clamped, when the pressure on the lever 23 is still further increased.

This further pressure shifts the lever 23 still further in the clockwise direction, or inwardly about its pivot, until it engages the control switch or the operating means for this switch. In the arrangement shown it engages the movable contact 20 of this switch and shifts it into engagement with the stationary contact 19, the spring support 21 yielding for this operation. This closes the electrical circuit to the electrodes 5 and 6, permitting current to flow between the electrodes, the high current flow in this low resistance circuit causing the temperature of the work members (in the example taken, the copper wires) to rise rapidly to a point at which solder will flow readily when placed in contact with these heated wires. In using shop models of this tool, it has been found that when one or more pieces of metal are held firmly between the electrodes, as described, the metal is brought to proper soldering temperature almost instantaneously when the switch is closed.

Experiments which have been conducted indicate that excessive clamping pressure of the electrodes retards heating of the work to some extent, due to the fact that the contact resistance between the electrodes and the work is thereby reduced. The novel construction and arrangement of this tool possesses an added advantage in that the clamping pressure of the electrodes is a function of the characteristics of the actuating spring 28, which may therefore be designed to provide the electrode clamping pressure which is determined to be the optimum for most efficient operation.

Although an elongated slot 26 in actuating lever 23 with a pin 25 has been shown as the limiting means for the lever 23, it will be understood the device is not limited to this specific construction, but that other suitable stop means may be employed. Although a lever overtravel stop means is not absolutely essential to the operation of this tool, it is a highly desirable feature in that it protects the switch operating mechanism against possible damage as a result of overpressure or overmovement of the actuating lever 23. It also prevents excessive movement of the electrode lever 7 under the thrust of the actuating spring 28 and the return spring 27.

To interrupt the flow of current through the electrodes after the temperature of the copper wires has been raised to a point at which the solder will readily flow, it is only necessary for the operator to decrease slightly the manual pressure on the actuating lever 23. A slight decrease

in this manual pressure permits this lever to retract or move upwardly under the thrust of the actuating spring 28. A slight counterclockwise or upward movement of this lever disengages it from the operating mechanism of the switch, or in this case the contact member 20, permitting the contacts to separate under action of the spring 21 and thus interrupt the flow of current through the electrodes. At this point the thrust of the actuating spring 28 against the electrode lever 7 is still sufficient to maintain the electrodes 5 and 6 in the clamping position. Thus the work, or in this case the two copper wires, are held firmly in position after the switch 19, 20 has been opened. This provides means for holding the work firmly while the solder is cooling after the current flow has been interrupted, and is a particularly important feature of this tool.

Further, while the work is held firmly between the electrodes 5 and 6, the control switch may be operated intermittently by slight changes in the manual pressure applied to the actuating lever 23, thus controlling the temperature of the work. This heat control may be used either to maintain an even temperature over prolonged periods or to gradually increase or decrease the temperature of the work, as is required in certain drawing and annealing operations.

Briefly, it will be seen from the above that this tool possesses a number of outstanding advantages over other tools available for similar use. Among the novel and advantageous features the following are believed to be particularly important:

(a) It provides means for holding the work firmly clamped between the current-carrying electrodes during the entire operation, regardless of whether or not current is actually flowing through the electrodes.

(b) It provides means for protecting the current-carrying electrodes against overstressing of the electrode material should excessive pressure be applied to the actuating lever.

(c) The current-carrying electrodes are automatically maintained in the open or ready position when the device is not in use.

(d) It includes a self-contained switch control means which is actuated by the same lever which changes the relative positions of the electrodes and applies the electrode clamping pressure. This eliminates the necessity for providing some external means for controlling the flow of current to the electrodes, and places the entire control of the device in a single manually operable actuating and control lever.

(e) The combination of clamping means for holding the work firmly between the electrodes, and a quick actuating and self-contained switch means for controlling the raising of the temperature of a piece of electrically-conducting material, provides means by which the operator when desired may readily maintain that temperature within reasonably accurate limits for a prolonged period, or it may be used for gradually raising or lowering the temperature of a piece of such material, as is required in certain drawing or annealing operations, or for brazing, soldering or welding together two or more pieces of such electrically-conducting material.

All of these features make for greater convenience, safety and efficiency, and for more accurate heat control at lower cost.

Having thus set forth the nature of my invention, I claim:

1. An electric soldering tool of the character

described comprising an oblong housing in the form of a hand grip and formed of electrically nonconducting material, a pair of work clamping electrodes mounted in said housing and projecting from one end thereof, at least one of said electrodes being pivoted so as to be movable toward and from the other to clamp and release work to be heated, electrical supply connections to said electrodes, said housing being provided with a longitudinal side opening, manually operable means for shifting the movable electrode toward the other to clamp the work between them comprising a hand lever of electrically nonconducting material pivoted in the housing and projecting at one edge through said opening, an actuating spring between the lever and the electrode so that force of the operating lever is transferred to the electrode through said spring, a return spring of less thrust than the actuating spring tending to shift the movable electrode to separate the electrodes, and a control switch in the supply connections operated by the manually operable lever arranged to close the circuit only after the electrodes engage the work.

2. An electric tool of the character described comprising an oblong housing of electrically nonconducting material forming a hand grip and provided with a longitudinal side opening, a pair of electrodes mounted in and projecting from one end of the housing, a lever in the housing mounting one of the electrodes for movement toward and from the other to clamp and release work to be heated, electrical supply connections to the electrodes, an operating hand lever of electrical nonconducting material pivotally mounted in the housing and projecting at one edge from one side thereof through said opening for manual operation, a spring between the second lever and the first to transfer pressure from the operating lever to the first lever to clamp the work between the electrodes, a return spring of less thrust than the first spring between the other side of the first lever and the housing tending to swing the first lever in the opposite direction to release the work, a control switch in the housing to control current to the electrodes, and means

operated by the operating lever for closing the switch and so spaced from said lever as to be operated only after the electrodes have been clamped on the work.

- 5 3. An electric tool of the character described comprising a substantially oval shaped housing of electrically nonconducting material to fit in the hand and form a hand grip and provided with an oblong longitudinal opening in one side, a pair of electrodes in the form of work clamping jaws projecting from one end of the housing, a lever pivotally mounted in the housing and providing a support for one of the electrodes, electrical current supply connections to the electrodes, an operating hand lever of electrically nonconducting material mounted in the housing and provided with a longitudinally curved edge projecting through said opening for manual operation, a coiled compression spring between the levers for transferring pressure from the operating lever to the first lever to clamp the work between the electrodes, a coiled compression spring of less thrust than the first spring on the opposite side of the first lever tending to shift the first lever in the opposite direction to release the work, a control switch in the housing to control the current to the electrodes, and means operated by the operating lever controlling the switch and so spaced from said lever as to close the switch only after the electrodes have been clamped on the work.
